UNITED STATES PATENT OFFICE

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT

ELECTRIC SWITCH

Application filed March 23, 1923. Serial No. 627,104.

My invention relates to electric switches, and particularly to a switch of the canopy type. The object of my invention is to provide a compact switch of efficient and economical construction, adapted for installation in the restricted space available in a canopy base, while nevertheless capable of safely controlling the circuit of a lamp mounted at the canopy.

10 In the accompanying drawings—

Fig. 1 is a section through a canopy installation with which a switch embodying my invention is associated;

15 Fig. 2 is an enlarged section through the switch;

Fig. 3 is a section on the line 3—3, Fig. 2;

Fig. 4 is a dropped perspective of the insulating base of the switch; and

20 Fig. 5 is a perspective of the switch housing.

In fixtures of the type illustrated it is common practice to cover the usual outlet box 6 with a decorative canopy 7. Such canopies are generally very shallow in order to hold 25 the lighting fixture 8 as close as practicable to the wall 9 into which the outlet box is set. Where it is desired to control the fixture circuit from the canopy, it is necessary to provide a very shallow switch which may be installed within the canopy plaque, while at 30 the same time the switch must be of suitable capacity to safely handle the lighting current. A suitable shallow switch construction for this purpose is provided by the present invention.

According to the present invention the switch comprises an insulating base built up from a group of plates or discs of insulation, such as fiber, which may be readily stamped 40 out to afford the necessary channels for the accommodation of conductors carried by one of the discs. The number of these disc-like members may be varied. An efficient base is provided, however, according to the present 45 construction, by the four discs 10, 11, 12 and 13 (Fig. 4). The disc 10 has riveted thereto at 14 and 15 two switch contact strips 16 and 17. The brush ends of these strips extend at right angles to and overlie one face of the 50 disc 10 on opposite sides of its axis, and are

offset through marginal notches with their bases 18 and 19 lying against the opposite side of the disc and secured to the latter by rivets. Integral with the strips and extending from the bases 18 and 19 are looped wire-receiving lugs 20 and 21 adapted to receive the bared ends of the pig-tail connections 22 and 23, which are soldered thereto and by which the switch is connected to the main 24 and branch wire 25 of the installation. 55 The main 26, is as usual, carried directly to the lamp receptacle of the candle socket 27.

The disc 11 is juxtaposed to the face of the disc 10 and is marginally notched at 28 and 29 to accommodate the terminal lugs 20 and 21 60 and the bases 18 and 19 of the contact strips.

The disc 12 is juxtaposed to the disc 11 and is marginally notched at 30 and 31 to accommodate the wire terminal lugs 20 and 21 65 which project through the disc 11.

The disc 13 forms a bottom closure which houses-in the conductors on the base and prevents accidental contact therewith. The disc 13 is of greater diameter than the discs 10, 11 and 12, and rests against the edge of 70 the cup-shaped metallic casing 32 which, as usual, is provided with an insulating lining 33. The margin of both the casing and its lining are notched at 34 to receive lugs 35, which project from each of the discs 10, 11 75 and 12, thus holding the base in fixed relation with respect to the casing. The latter is also notched at 36 and 37 on opposite sides of its axis to accommodate the pig-tails 22 and 23 which project therethrough from the terminal lugs 20 and 21, which are carried by the disc 10 and lie in a plane at right angles to the axis of the switch casing.

The several discs 10 to 13 inclusive are all centrally pierced in register at 38 to accommodate the inner reduced end of the switch spindle 39 which extends therethrough, and is spun over at 40 against a bearing washer 41 which lies against the outer face of the closure disc 13. Arranged on the spindle is a 90 rotary switch member 42 having peripheral ratchet teeth. The rotary switch bar 43 which is carried thereby is provided with contact wings 44 which overlie alternate ratchet teeth and make and break contact 95 100.

with the spring contacts 16 and 17 on the operation of the switch. A driving connection between the spindle and switch piece is established by lugs 45 struck from the spindle and taking into notches 46 in the rotary switch piece 42.

Adjacent the switch piece the spindle 39 has an enlarged hub 47, the shoulder 48 of which bears upon the rotary switch piece 42 through an insulating washer 49, which prevents contact between the spindle and the switch bar 43. The spindle is steadied by the hub 47 which lies within the bushing 50 set into and rigidly secured to the neck 51 of the casing 32. At its outer end the spindle is threaded at 52 to receive a draw-up nut 53 and also the operating thumb piece 54. The draw-up nut 53 bears upon the outer end of the bushing 50 and holds the casing 32 seated against the closure disc 13, and thus maintains the parts in properly housed relation.

Engaged on the threaded bushing 50 are clamping nuts 55 and 56, between which the canopy 7 is engaged, and by means of which the switch is supported in the hole 57 formed therein for its accommodation.

The various parts of the switch mechanism are readily formed from sheet material by stamping and forming operations. Their assembly upon the switch spindle 39, after the pig-tail connections have been soldered to their terminals, is readily accomplished by slipping the parts over the reduced end of the spindle until they butt against the shoulder 48 of the enlarged area 47. They are permanently secured in position by spinning over the end 40 of the spindle. The casing 32 may then be slipped over the opposite end of the spindle and secured in position by means of the draw-up nut 53. The latter is of less diameter than the bushing 50, so that the nuts 55 and 56 may then be threaded on the latter and the thumb piece 54 attached. The make and break operation of the switch is accomplished by the rotation of the spindle in well understood manner.

The construction is simple and efficient in operation and presents the marked practical advantage of leading the pig-tails 22 and 23 from the sides of the casing—thus making it possible to install the switch in a much shallower canopy than can be used with switches in which the leads extend from the inner end of the switch in the direction of its axis.

Various modifications in detail will occur to those skilled in the art, without departing from what I claim as my invention.

I claim:

1. In an electric switch, an insulating base comprising a group of juxtaposed plates of insulating sheet material, the outer plate of said group being of greater diameter than the others, a combined wire terminal and switch contact element secured against the face of an intermediate one of said plates

and extending toward the margin thereof in the plane of an adjacent plate and thence over the margin to locate the switch contact portion thereof above said plates, said adjacent plate being notched to accommodate said wire terminal, together with marginal lugs on the contact carrier and notched plates, and a switch cover resting on the projecting marginal area of said outer plate and surrounding the other plates, said cover being notched to receive said marginal lugs to hold the engaged plates in register and apertured to accommodate lead wires.

2. In an electric switch, a base comprising a number of juxtaposed plates of insulating material, a number of wire terminals secured on one side of an intermediate plate of said group, switch contacts on the opposite side of said plate and spaced therefrom to lie above the plate that rests on said intermediate plate, said terminals and switch contacts being formed as integral pieces with a connecting portion extending from said terminals over the margin of said intermediate plate to said contacts, whereby the contacts are supported from said intermediate plate.

In testimony whereof I have signed my name to this specification.

GEORGE B. THOMAS.
